UNITED STATES PATENT OFFICE.

RUDOLF OCHSCHIM, OF BERLIN, GERMANY.

GRINDING, SMOOTHING, ROUGHENING, AND POLISHING MACHINE.

SPECIFICATION forming part of Letters Patent No. 723,481, dated March 24, 1903.

Application filed October 3, 1901. Serial No. 77,446. (No model.)

To all whom it may concern:

Be it known that I, RUDOLF OCHSCHIM, pianoforte-maker, a subject of the King of Prussia, German Emperor, residing at No. 47

5 Frankfurter Allee, Berlin, in the Kingdom of Prussia, German Empire, have invented certain new and useful Improvements in Grinding, Smoothing, Roughening, and Polishing Machines, of which the following is a specification.

This invention relates to the arrangement of a horizontally-acting machine the spindle of which may be automatically raised and may be automatically displaced or moved to 15 and fro in a horizontal direction and upon the spindle of which is arranged a tool adapted to be adjusted longitudinally or axially during work and to be secured in place or fixed in position, if necessary, that the tool 20 may be a grinding-tool, (so-called "grinding-head,") if desired.

The main object of this machine is to grind massive or solid parts of wood or such covered with a thin veneer or veneers without 25 destroying the pores of the wood or grinding it through, if it is a veneer, be it ever so thin, an indispensable requirement being that the tool which is automatically raised off the work-piece may be lowered down upon the 30 same by the feel and may be adjusted in its position upon the spindle during work. This machine may be used, however, also for grinding and polishing or working upon other materials than wood.

35 In order to make my invention more clear, I refer to the accompanying drawings, in which similar letters denote similar parts throughout the several views, and in which—

Figure 1 is a front view of the machine; 40 Fig. 2, a plan of the lever arrangement for operating the slide carrying the working spindle; Fig. 3, a vertical section of the machine; Fig. 4, a plan of the means for actuating the working spindle. Figs. 5 and 5^a are a front 45 view and a side view, partly in section, of one of the slides for carrying and operating the working spindle.

Two slides *a* *a'*, arranged one opposite to the other in the frame of the machine and 50 adapted to be moved by levers *g*, having counterpoises *z* and being supported by movable rods *i*, fulcrumed at *h*, Figs. 1 to 3, and

connected by a bar *h*, form at their lower ends bearings *d*, carrying the working spindle *b*, the middle part of which has a thread 55 *b'*. The bearing *d* of the slide *a* has a rotary socket or box *e* with a hand-wheel *c*, and a feather located in said box takes into a groove provided in the spindle, so that this latter is rotated by the box if this is turned by the 60 wheel *c*, there being displaced by this movement a tool *m*—for instance, a so-called "grinding-head" or the like—arranged upon the threaded portion of the spindle, provided the screw *n* be loosened. 65

Below the working spindle and the tool is arranged a table *y*, which may be moved crosswise to the direction of the spindle. Said table is supported by rolls *u* upon rails *v* and is coupled to a threaded spindle *u*, having a 70 hand-wheel *w* and taking into a nut *w'*, secured to the table, so that this latter may be moved as well as fixed in position. There may be located inside the table a device or contrivance for displacing the work-piece *x* 75 or *x'* upon the table rectangularly to its other direction, such device consisting, for instance, of parts *j* *j'* *j''*, as shown. These parts are known and need not, therefore, be described. 80

The to-and-fro movement of the spindle *b*, with its tool, may be effected by any appropriate means. According to Figs. 1, 3, and 4 the spindle is connected to a rotary disk *o*, fixed upon one shaft with pulleys *s*, one of 85 which is fast upon said shaft. The connection is effected by a rod *l*, attached at one end to a pin *p'* of a collar *p*, fixed to the spindle, and at the other end to a pin *o'*, fixed to said rotary disk. By these means or other ones 90 the spindle *b* is displaced lengthwise to and fro in the bearings *d*, and at the same time it may be raised or lowered by means of the counterpoises at said levers tending to raise the spindle automatically as soon as no pressure is exerted upon the bar *h*. Besides this, the work-piece itself may be displaced horizontally below the tool in two directions by aid 95 of the means aforescribed. 100

Having now described my invention, what I desire to secure by Letters Patent is—

In a machine for grinding, smoothing, rough-

ening, and polishing purposes especially for wooden-work pieces and veneers, the combination with two parallel slides mounted to move in vertical guides, of two levers connected pivotally at a distance from their fulcrums with said two slides, yielding means for supporting the fulcrums of said levers, a horizontal rod rigidly connecting the ends of said two levers and serving as a handle for moving up and down said two slides, counterweights for raising said rod and levers with said slides when released, said two slides being provided at their lower ends with bearings, a horizontal screw-threaded spindle mounted to turn and to move lengthwise in said bearings, an adjustable pin secured on said spindle, a driving-shaft carrying a crank with a pin, a pitman connecting said adjust-

able pin with said crank-pin, so that during the revolution of said driving-shaft said spindle is put into a reciprocating longitudinal movement, an adjustable nut for the screw-threaded part of said spindle and adapted for receiving and holding the tool, means for shifting said nut with the tool by turning said spindle, a carriage for holding the work-piece and arranged to move beneath the tool in directions at right angles to said spindle, and means for shifting said carriage in either direction, substantially as set forth. 30

In witness whereof I have hereunto set my hand in presence of two witnesses.

RUDOLF OCHSCHIM.
